UNITED STATES PATENT OFFICE

WILLIAM M. CUMMER, OF CLEVELAND, OHIO.

DRYING-CYLINDER.

No. 876,440.

Specification of Letters Patent.

Patented Jan. 14, 1908.

Application filed April 29, 1907. Serial No. 370,804.

To all whom it may concern:

Be it known that I, WILLIAM M. CUMMER, a citizen of the United States, residing at Cleveland, in the county of Cuyahoga and State of Ohio, have invented certain new and useful Improvements in Drying-Cylinders, and do declare that the following is a full, clear, and exact description of the invention, which will enable others skilled in the art to which it appertains to make and use the same.

My invention relates to a new and original construction of drying cylinder adapted to be installed in a drying apparatus, all substantially as shown and described and particularly pointed out in the claims.

In the accompanying drawings, Figure 1 is a longitudinal sectional elevation of a drying apparatus embodying my new cylinder in working relation, and Fig. 2 is a cross section of the cylinder alone.

This invention is an improvement on the style of cylinder shown in my application, Ser. No. 352,858, filed January 18, 1907, and pending concurrently herewith, as will hereinafter fully appear. Thus, C represents the cylinder as an entirety, which consists of a series of six separate longitudinal sections c in this instance, substantially segmental in cross section and arranged eccentrically to the axis of the cylinder as seen by comparison with concentric inner and outer circles a and a' respectively. Said longitudinal sections or plates are spaced apart and supported at their meeting or adjacent edges successively by intervening bars, strips or ribs B to which the edges of the plates are riveted and which operate as longitudinal supporting members for the cylinder, giving it the needed strength in all its parts as well as serving to unite the sections. Said bars or rails furthermore are provided with openings b through the web thereof which form draft passages or openings through which the products of combustion pass from the furnace and enter the cylinder into direct contact with the material under treatment, and the usual suction fan F at the front of the cylinder stimulates draft through these openings. Now, having entered the body of the cylinder through said draft openings I provide an internal construction which performs several important offices, as will be seen. Thus, I build up an entering space or chamber just within said openings b which in a sense continues or extends the draft passage

at least partially above the body or mass of material that ordinarily accumulates at the bottom of the cylinder to greater or less depth, so that the material will be prevented from crowding out through said draft openings or filling them up to cut off the draft, and then there is the further utility in the construction of said chamber in that its walls guard said openings against the material as it is dropped or cascaded from the lifts as they turn the material loose from about the top of the cylinder in successive rotation, and also of serving as lifts and deflectors for the material. Now, having reference especially to the construction of these internal draft chambers or passages, it is seen that there is a wall 4 for each member referred to herein as the shorter or outer wall which is built upon the edge of the higher of the two meeting plates while the opposite or inner wall 5 referred to also as a guard wall on account of its function, is parallel to wall 4 and is erected upon the relatively lower or outer meeting section or plate c, looking at the bottom of Fig. 2. Said wall 5 not only runs parallel to wall 4 but in straight lines to substantially the same level as the inner edge thereof and is deflected thence at an angle of approximately 45 degrees, or less, across the said draft chamber or space and across the plane of wall 4 to a point that brings its edge well into the body of the cylinder, and into complete shielding relation to its chamber and the exit therefrom into the cylinder. Of course, there is nothing arbitrary in these relative positions, depths or widths of said walls, the idea of the inclined inner portion of wall or plate 5 being to serve the several functions and purposes hereinbefore specified and also to shed and deflect the material cascaded from about or near the top of the cylinder into the space behind said chamber guard plate 5, as will readily be seen at the bottom of Fig. 2. It will be understood, also, that the foregoing description has reference more especially to conditions and constructions as they are found at the bottom of the cylinder, where in any event the cylinder is subjected to all its more important tests of operation, and on the assumption that having a construction which meets the conditions or needs at the bottom of the cylinder there is no occasion for apprehension about operations at the side and top of the cylinder as it rotates.

Between the walls 4 and 5 of the draft chambers I provide each section c with a plu-

rality of more or less upwardly curved lift blades 7, which carry their full capacity of material upward to near the top of the cylinder before discharge therefrom begins, and 5 then the discharge is gradual and while the fall of the material may be more or less upon the inner sides of walls 5 next beneath the said material is finally discharged or cascaded from the top of the cylinder to the bottom, 10 and in its fall is deflected by the outer inclined surfaces of guard walls 5 behind the same.

One of the important advantages of the present construction of the guard walls, 5, as 15 compared with the right angled corresponding walls in the application upon which this is an improvement, is that these inclined guards discharge such material as falls upon them from lifts 7 from the top of the cylinder, 20 thus causing the material to cascade through the entire width and depth of the cylinder and become exposed directly to the strong current of heat that passes through the body of the cylinder under the influence of the 25 suction fan at the front, whereas in the right angled form of the said walls, and also in right angled lift blades, the material is carried past the center of the cylinder to the opposite side before it is entirely discharged, 30 and in such discharge it tends to fall on the backs of the other lift blades upon that side and against the side of cylinder and does not get the benefit of the long drop through the 35 volume of heat in the middle of the cylinder as in the present construction. The transversely curved lifts 7 likewise contribute to this better result as compared with right angled lifts used commonly heretofore. Said lifts are concavo-convex in cross section but 40 their concave side is uppermost.

What I claim is:

1. A drying cylinder formed in longitudinal sections having strengthening ribs between adjacent edges of said sections provided with draft openings, and walled draft 45 passages inside the cylinder into which said openings discharge having varying elevation the higher of said walls being bent to an angle of inclination at their inner portions 50 across the plane of the opposite walls into guarding relations.

2. A drying cylinder having longitudinal draft openings through the wall thereof and draft chambers in said cylinder having parallel walls of different elevation on opposite 55 sides lengthwise, one of said walls being bent at an angle of inclination of approximately forty-five degrees laterally and projected across the plane of the opposite wall.

60 3. A drying cylinder consisting of several longitudinal segmental sections having their meeting edges spaced apart and draft open-

ings between said sections and a walled draft chamber next within said openings, one wall of said chamber being erected on each of said meeting sections and the higher wall having an inclined extension projecting across said chamber and into the interior of the cylinder, thereby serving as a lift on one side and as a deflector on the other and as a guard for said chamber.

4. A drying cylinder formed in segmental sections lengthwise eccentrically arranged, spacing pieces between the meeting edges of said sections provided with draft openings and draft chambers lengthwise next within said openings provided with parallel walls, one wall being fixed on each meeting section and the higher wall having an inclined inner lifting and deflecting portion, and transversely curved lift blades between said chambers.

5. A drying cylinder having draft openings through the wall thereof and draft chambers in said cylinder provided with parallel continuous walls on opposite sides of said openings, said walls being of different elevations and the higher of said walls having an inclined inner portion projecting toward the plane of the other wall.

6. A drying cylinder having lift blades curved in cross section, and having longitudinal chambers, and the walls of one side of said chambers extending into said cylinder and having their inner portions arranged to receive and carry a portion of the discharge from said lift blades.

7. A drying cylinder having a series of walled draft chambers lengthwise inside and the walls on one side of said chambers having inner extensions at an inclination to the walls on the opposite sides of said chambers and overlapping the same, and lift blades with concave carrying sides arranged between said walled chambers.

8. A rotatable drying cylinder formed of a plurality of segmental sections spaced apart at their edges to provide longitudinal draft intakes, and longitudinal deflecting plates within the cylinder having extensions projecting over said draft intakes to guard against the escape of material from said cylinder when rotated and providing cascading lift blades for the material and walls opposite said deflecting plates and parallel thereto, 110 said walls and plates respectively forming sides of draft chambers.

In testimony whereof I sign this specification in the presence of two witnesses.

WILLIAM M. CUMMER.
